UNITED STATES PATENT OFFICE

EVERETT WORTHINGTON, OF CHICAGO, ILLINOIS, ASSIGNOR TO THE STROMEERG-CARLSON TELEPHONE MANUFACTURING COMPANY, OF ROCHESTER, NEW YORK, A CORPORATION OF NEW YORK

DESIGN FOR A RADIOCABINET OR SIMILAR ARTICLE

Application filed April 7, 1930. Serial No. 35,179. Term of patent 3½ years.

To all whom it may concern:

Be it known that I, EVERETT WORTHINGTON, a citizen of the United States, residing at Chicago, county of Cook, State of Illinois, have invented a new, original, and ornamental Design for Radiocabinet or Similar Article, of which the following is the specification, reference being had to the accompanying drawing, forming a part thereof.

The single figure is a perspective view of a cabinet showing my new design.

I claim:

The ornamental design for a radio cabinet or similar article as shown.

EVERETT WORTHINGTON.
